UNITED STATES PATENT OFFICE.

HARRY C. HANFORD AND MARTIN H. LANG, OF MINNEAPOLIS, MINNESOTA.

RADIO MAST SEAT.

Application filed March 12, 1923. Serial No. 624,390.

To all whom it may concern:

Be it known that we, HARRY C. HANFORD and MARTIN H. LANG, citizens of the United States, residing at Minneapolis, in the county of Hennepin and State of Minnesota, have invented certain new and useful Improvements in Radio Mast Seats, and we do hereby declare the following to be a full, clear, and exact description of the invention, such as will enable others skilled in the art to which it appertains to make and use the same.

Our invention provides a simple and highly efficient mast seat especially adapted for holding radio masts, flag poles and the like, and, generally stated, the invention consists of the novel construction and combinations of parts hereinafter described and defined in the claims.

This improved mast seat is of such construction that it will fit any type of roof, whether flat, a plain peak or peak with a ridge roll, and, moreover, it is adjustable to different roof angles and is adapted to be applied to a roof or other structure in position to support a mast or pole vertically, horizontally or at an oblique angle, if desired.

In the accompanying drawings, which illustrate the invention, like characters indicate like parts throughout the several views.

Referring to the drawings:

Fig. 1 is a side elevation showing the improved mast seat;

Fig. 2 is an end elevation of the same;

Figs. 3, 4 and 5 are side elevations showing the mast seat applied in different ways; and

Fig. 6 is a view corresponding to Fig. 2, but illustrating a slightly modified construction.

Figs. 1 to 5, inclusive, illustrate the improved mast seat designed as a cast metal structure, and this construction will first be described. The receiving socket of the mast seat, which is adapted to receive and hold the base end of the mast or pole *y*, is made in two semi-cylindrical sections 7 cast integral with ridge flanges 8, which, in length, are much wider than the socket sections and are formed with abutting upwardly extended ears 9 through which nut-

equipped bolts 10 are passed to rigidly connect the two sections.

The ridge flanges 8 are thus rigidly connected and it is important to note that they have a downward convergence and form, at the base of the socket, an approximately cylindrical concave surface 11, which, as will presently be noted, is adapted to span and clear a ridge roll such as the customary semi-tubular galvanized metal ridge roll found in very extensive use.

At the lower edges of their ends, the ridge flanges 8 are formed with hinge lugs 12 to which, by means of rivets 13, the lugs 14 of adjustable roof flanges 15 are directly hinged. By means of wood screws, not shown, applied through screw holes 16 in the flanges 15, the latter are adapted to be directly anchored to a roof or other building structure and any one of the several adjustments shown in Figs. 2, 3, 4 and 5, or in intermediate positions. Obviously, the hinge or pivotal actions of the so-called roof flanges make it possible to fit the device to any roof or similar structure, whether flat, angular, oblique or perpendicular. Obviously, when the nuts of the bolts 10 are tightened, the mast or pole *y* may be very firmly clamped in the socket.

Fig. 2 shows the device adjusted for application to the ridge of the roof having a pitch of approximately forty-five degrees. Fig. 3 illustrates the use of the device to support a mast in a vertical position from a flat surface. Fig. 4 shows the device used to support a mast in a vertical position on the surface of an oblique roof, which has a pitch of approximately forty-five degrees, and in this arrangement, a spacing block *y*' is placed between the roof and one of the roof flanges 15. In the arrangement illustrated in Fig. 5, the device is applied to the side and top of a rectangular structure and positioned to support the pole or mast in a horizontal position. In Fig. 2, the numeral 17 indicates a sheet metal ridge roll having an approximately semi-cylindrical ridge roll 18. This view, Fig. 2, shows the important purpose of the concave surface 11. Fig. 6 shows substantially the construction already described, but in which the elements of the seat are stamped from sheet

metal. In this construction, the socket-forming sections 7^a are formed with ears 9^a connected by short nut-equipped bolts 10^a, and the ridge flanges 8^a are formed with 5 turned hinge lugs 12^a, which, by pins or rivets 13^a, are connected to lugs of the roof flanges 15^a.

What we claim is:

1. A mast seat comprising an approximately semi-cylindrical body adapted to 10 clear a ridge roll, said semi-cylindrical body

at its intermediate portion having an up-standing socket and having anchoring flanges directly hinged to its opposite edges.

2. The structure defined in claim 1 in 15 which said body and socket are vertically split and have means rigidly connecting its sections together.

In testimony whereof we affix our signatures:

HARRY C. HANFORD.
MARTIN H. LANG.
